UNITED STATES PATENT OFFICE

AXEL PERSON, OF ATTLEBORO, MASSACHUSETTS, ASSIGNOR TO HARVEY CLAP & CO.,
OF ATTLEBORO, MASSACHUSETTS, A PARTNERSHIP

BRACELET CONSTRUCTION

Application filed March 29, 1927. Serial No. 179,310.

This invention relates to bracelet construction and more particularly to a bracelet connecting device or clasp.

One of the objects of the invention is to provide a construction of the above nature which is practical and efficient. Another object is to provide a construction of the above nature having a dependable lock. Another object is to provide a construction of the above nature in which the freedom of action and flexibility of the bracelet are not unduly impaired by the connector construction. Another object is to provide a construction of the above nature which is simple and strong. Another object is to provide a construction of the above nature which is neat and attractive in appearance. Other objects will be in part obvious or in part pointed out hereinafter.

20 The invention accordingly consists in the features of construction, combinations of elements, and arrangements of parts as will be exemplified in the structure to be hereinafter described and the scope of the application of which will be indicated in the following claims.

In the accompanying drawing in which is shown one of the various possible embodiments of this invention,

30 Figure 1 is a plan view of a bracelet shown somewhat diagrammatically;

Figure 2 is a plan view of the middle portion of the bracelet shown in enlarged detail;

Figure 3 is a side elevation of the parts shown in Figure 2;

Figure 4 is a longitudinal section taken substantially along the line 4—4 of Figure 2;

Figure 5 is a plan view showing the clasp disconnected or opened;

40 Figure 6 is a section taken along the line 6—6 of Figure 4, and

Figure 7 is a section taken along the line 7—7 of Figure 4.

Similar reference characters refer to similar parts throughout the several views of the drawing.

Referring now to the drawing in detail, there is shown in Figure 1 a bracelet which is adapted for use in connection with a wrist watch or the like. The body of the bracelet

is made up of a series of bracelet units or links 10 which are connected together as will be described hereinafter, and at each end of the bracelet is shown a clasp or connector 11 for attachment to the wrist watch. Adjacent the middle portion of this bracelet is a detachable connector or clasp which is indicated generally by the numeral 12 in Figure 1 and which detachably connects together the two bracelet portions on either side thereof. When the bracelet is in use, it may be placed in position upon or removed from the wrist with the greatest convenience by disconnecting the clasp 12, without requiring that the bracelet ends be disconnected from the wrist watch or other device with which it is used. Although this construction is thus of particular advantage in a bracelet for wrist watches or the like, it is to be understood that certain features of the invention may be employed to great advantage in various other types of bracelets.

Referring now to Figure 4, each of the bracelet units 10 comprising the body of the bracelet consists of an outer box-like link member 13 and an inner link member 14 which is slidable longitudinally in the outer link member. A spring 15 bearing against the end wall 14^a of the inner link member and against a suitable abutment 13^a of the outer link member, normally holds the parts in the position shown in the drawing with the inner link member of each unit drawn into the outer link member thereof. The outer link members have top walls and depending side walls and, extending between these side walls adjacent one end thereof, is a transverse pin or pintle 16 which is preferably hollow, as shown. The adjoining bracelet units are hinged together by the end 14^b of the inner link member hooking over the pin 16 of the adjoining unit. Preferably the connections between the adjoining units are made detachable as by splitting the bottom wall of the inner link, as shown at 17 in Figure 4, so that units may be taken from or added to the bracelet to vary its length.

The bracelet is thus extensible, the sliding inner link members 14 permitting a substantial increase in the length of the bracelet.

when it is stretched out. Moreover, the bracelet is flexible and readily conforms to the contour of the wrist, the respective units thereof pivoting freely with respect to each other about the pins 16. These pins 16, in the embodiment shown, extend through the side walls of the outer link members and are headed over against the outer surfaces thereof.

Considering now more particularly the connector which has been designated generally by the numeral 12 in Figure 1, as is seen in Figure 4, this connector is associated with a link member 18 which is of slightly different construction than the bracelet units 10 which form the body of the bracelet. This link member 18 is a hollow member having a top wall 19, side walls 20 and a bottom wall 21. Its size and general outer contour are preferably substantially the same as those of the outer box-like link members 13 of the bracelet units 10. Between the side walls 20 thereof adjacent the left-hand end, as viewed in Figure 4, extends a pin 22 which is similar to the pins 16 and which is located upon the link member 18 in a position corresponding to that of the pins 16 of the link members 13. The sliding link member 14 of the adjoining bracelet unit to the left of the member 18 is hooked over the pin 22 so that this adjoining bracelet and the member 18 are hingedly connected together substantially as are the bracelet units 10 forming the body of the bracelet.

Secured to the bracelet unit 10 which is at the end of the member 18 remote from the pin 22, or at the right of the member 18, as viewed in Figure 4, is a spring catch member 23, which enters the member 18 and detachably springs into engagement therewith. This spring member 23 is pivoted upon the pin 16 of the adjoining link member 13. It preferably comprises a flat metal member bent upon itself to the contour shown in Figure 4, having a lower part 23^a extending along the inner side of the bottom wall 21 and an upper part 23^b which tends to spring upwardly away from the part 23^a. The part 23^b is provided adjacent its right-hand end with a pair of upstanding side flanges 24 and 25 which terminate in a pair of ears 26 and 27 respectively, which are swiveled upon the pin 16.

In Figure 4 the spring member 23 is shown drawn out from the member 18, thereby disconnecting the two halves of the bracelet. When the two bracelet halves are brought together and the part 23 is entered into the member 18, the end edge 23^c of the spring 23 snaps beneath a depending lip 19^a (Figure 4) at the right-hand end of the top wall 19 of the member 18, thereby locking the spring catch 23 within the member 18 and connecting the bracelet halves. The part 23^b of the spring catch has formed thereon an upwardly pro-

jecting lug 28 which slides through a slot 29 in the wall 19. By depressing the lug 28 and thereby springing the part 23^b downwardly so as to permit the edge 23^c to clear the depending lip 16, the parts may be separated. 70

From the description thus far, it will be seen that there is provided a connector or clasp for the bracelet which is very convenient to operate. The connection is made by simply sliding the spring catch member 23 into the part 18, and the catch is released by a slight pressure upon the lug 28 to depress the spring 23^b. Moreover, it will be seen that this clasp does not interfere with the flexibility of the bracelet. The spring catch 23, 75 swiveled upon the pin 16 of the adjoining right-hand bracelet unit 10, forms a hinged connection, and the left-hand end of the clasp member 18 is hinged to the adjoining bracelet unit also. The side flanges 24 and 25 of the member 23 fit snugly within the side walls 20 of the member 18 and thus strengthen and 80 reinforce the connection. 85

As is best seen in Figures 2 and 3, exterior of the link member 18 is a member 30 which serves as a lock for this connector or clasp. This member 30 has a top wall 31 which, when the lock is operative, rests against the top wall 19 of the member 18, and depending therefrom are side walls or flanges 32 and 33 which embrace the sides of the member 18. This lock member 30 is pivotally mounted upon the member 18 to swing into and out of operative position, and this pivotal mounting is preferably accomplished by the end portion 22^a of the pin 22 passing through the depending flanges 32 and 33 adjacent the left-hand ends thereof, as viewed in the drawing. In Figure 5 the lock 30 is swung upwardly to inoperative position. When it is operative, as shown in Figures 2-4, its right-hand end portion preferably overlaps the end portion of the adjoining bracelet unit 10. The metal of the side flanges 32 and 33 is bent outwardly, as shown at 34 and 35 respectively, and these portions snap over the projecting ends 16^a of the pin 16, upon which the spring catch 23 is pivoted, to yieldingly hold the lock in operative position. 100 105

In the top wall 31 of the lock 30 is an opening 36 into which the lug 28 of the spring catch projects. The part 31, thus embracing the lug 28, positively prevents the spring catch member 23 from being drawn out of the link member 18 to disconnect the catch. 110 115

It will be seen that this construction is simple and very compact. Moreover, the locking member 30 does not interfere with the relative swinging between the link member 18 and the adjoining bracelet unit, the projecting end portions 16^a of the pin 16 turning freely beneath the parts 34 and 35 of the lock as the hinging or relative swinging takes place. In the mounting of the lock upon the link member 18 the same pin 22 is utilized 120 125 130

which serves to pivotally connect the member 18 and the adjoining bracelet unit at the left or rear of the clasp. The springing of the parts 34 and 35 over the projecting end portions of the pin 16 dependably holds the lock in operative position, but with slight effort the lock may be swung about the pin 22^a to the inoperative position shown in Figure 5, whereupon the lock 28 may be depressed to open the clasp.

As many possible embodiments may be made of the above invention, and as many changes might be made in the embodiment above set forth, it is to be understood that all matter hereinbefore set forth or shown in the accompanying drawing is to be interpreted as illustrative and not in a limiting sense.

I claim as my invention:

1. In bracelet construction, in combination, a bracelet member having adjacent one end thereof a transversely extending pin, a catch member mounted upon said pin and extending outwardly from the end of said bracelet member, a second bracelet member detachably connected to said first bracelet member by said catch member, and a lock for said catch member comprising a part mounted upon said second bracelet member for movement into and out of operative position and means thereon adapted when operative to embrace the ends of said pin.

2. In bracelet construction, in combination, a bracelet link member having adjacent one end thereof a transverse pin for connection with an adjoining link, a second link member adjoining said first link member at the end thereof remote from said pin, a spring catch member detachably connecting said two link members, and a lock for said spring catch pivotally mounted upon said pin for swinging movement into and out of operative position.

3. In bracelet construction, in combination, a bracelet link member having adjacent one end thereof a transverse pin for connection with an adjoining link, a second link member adjoining said first link member at the end thereof remote from said pin, said second link member having a transverse pin, a member mounted upon said pin of said second link member and entering said first link member to detachably connect said two link members, and a locking member pivoted upon said pin of said first link member to swing into and out of operative position and having parts adapted when operative to overlap said second link member and embrace the ends of said pin thereof.

4. In bracelet construction, in combination, a link member having side walls, a pin extending between said side walls and having end portions projecting outwardly therethrough, a second link member, means mounted upon said pin between said side walls and projecting into said second link, and means upon said

second link detachably engaging said projecting end portions of said pin.

5. In bracelet construction, in combination, a pair of bracelet members, means detachably connecting said members comprising a spring catch member pivoted upon one of said members to swing about an axis extending substantially transversely thereof and entering and springing into engagement with the other of said members, and a lock for said catch comprising a member mounted upon said last bracelet member for movement into and out of operative position and adapted when operative to overlap said first bracelet member, and means upon said first bracelet member with which said lock member engages to yieldingly hold said lock in operative position, said means being substantially in line with said axis about which said spring catch is pivoted to permit said two bracelet members to swing relative to each other when said catch and said lock are operative.

6. In bracelet construction, in combination, a link member having a top wall and side walls, a pin extending between said side walls adjacent one end for connection with an adjoining link, the ends of said pin projecting outwardly through said side walls, a second link member adjoining said first link member at the end thereof remote from said pin and having side walls, a pin extending between said side walls of said second link member and having end portions projecting outwardly therethrough, a spring catch member pivoted upon said last pin and projecting therefrom into said first link member and springing into engagement therewith, and a lock for said catch comprising a member pivoted upon the projecting ends of said pin of said first link member to swing into and out of operative position, said lock member having a pair of parts which snap over the projecting ends of said pin of said second link member to yieldingly hold said lock in operative position.

7. In bracelet construction, in combination, a bracelet member having adjacent one end thereof a transverse pin adapted for making connection with an adjoining bracelet member, a second bracelet member adjoining said first bracelet member at the end thereof remote from said pin, said last bracelet member having a transverse pin, a member mounted upon said pin of said last bracelet member and entering said first bracelet member to detachably connect said two bracelet members, and a locking member pivoted upon said pin of said first bracelet member and adapted to swing thereon into and out of an operative position in which it cooperates with said first connecting member in connecting said two bracelet members.

8. In bracelet construction, in combination, a bracelet link member having adjacent one end thereof a transverse pin adapted for mak-

- ing connection with an adjoining link, a second link member at the end of said first link member remote from said pin, a spring catch member mounted upon one of said link members and adapted to enter the other of said link members and spring into engagement therewith, and a lock for said spring catch comprising a member having a pair of spaced arms pivoted upon said pin and a part connecting said spaced arms, said spaced arms resting exteriorly of the sides of said first bracelet link and said connecting part resting exterior of the upper surface thereof when said lock is swung into operative position.
9. In bracelet construction, in combination, a bracelet link member having adjacent one end thereof a transverse pin adapted for making connection with an adjoining link, a second link member at the end of said first link member remote from said pin, a spring catch member detachably connecting said two link members, and a lock for said spring catch comprising a member having a pair of spaced arms pivoted upon said pin and a part connecting said spaced arms, said spaced arms resting exterior of the sides of said first bracelet link and said connecting part resting exterior of the upper surface thereof when said lock is swung into operative position, said
- 25 30 35 40 45 50 55 60 65 70 75 80 85 90 95 100 105 110 115 120 125 130
- spring catch member and said top part of said lock having a projection and recess which cooperate in locking the two bracelet link members together when said lock is in operative position.
10. In bracelet construction, in combination, a link member having a top wall and side walls, a pin extending between said side walls adjacent one end for connection with an adjoining link, the ends of said pin projecting outwardly through said side walls, a second link member adjoining said first link member at the end thereof remote from said pin and having side walls, a pin extending between said side walls of said second link member and having end portions projecting outwardly therethrough, a spring catch member pivoted upon said last pin and projecting therefrom into said first link member and springing into engagement therewith, and a lock for said catch comprising a member pivoted upon the projecting ends of said pin of said first link member to swing into and out of operative position, said lock member having a pair of side parts which snap over the projecting ends of said pin of said second link member to yieldingly hold said lock in operative position, and having a portion connecting said side parts which rest against the top wall of said first link member, said connecting part and said spring catch member having a projection and recess which cooperate to lock said spring catch member against removal from operative position.
11. In bracelet construction, in combination, a pair of adjacent bracelet members, a

spring catch detachably connecting said bracelet members together, pivotal means mounting said catch upon one of said members, and providing projecting means upon the sides of said one member, a lock for said catch comprising a member mounted upon the other of said members for movement into and out of operative position and adapted when operative to embrace the sides of said one bracelet member, and means provided upon said lock member adapted to snap over said projecting means yieldingly to hold said lock member in operative position.

In testimony whereof, I have signed my name to this specification this 19th day of March A. D. 1927.

AXEL PERSON.
